UNITED STATES PATENT OFFICE

RALZA B. FREEMAN, OF BLOSSBURG, PENNSYLVANIA.

DESIGN FOR A PIN OR BADGE.

Specification forming part of Design No. **7,425**, dated May 12, 1874; application filed March 14, 1874.
[Term of Patent 7 years.]

To all whom it may concern:

Be it known that I, RALZA B. FREEMAN, of the borough of Blossburg, county of Tioga, State of Pennsylvania, have invented or produced a new and original Design for a Miners' National Association Pin or Badge, of which the following is a specification:

My design is fully represented in the accompanying drawing, and is formed by the letter N as a center, arranged in connection with a pick, shovel, and sledge, substantially as shown. Above this letter and implements is the letter M, and below the letter A. The letters M N A are the initials of the Miners' National Association; and although the style

of the letters may be somewhat changed, the design is essentially as stated.

The said letters and characters are to be cut, stamped, or engraved upon or into metal, stone, or other material, and may be printed or photographed upon paper, cloth, or any other substance whatsoever.

What I claim is—

The design for a pin or badge formed by the letters and implements substantially as shown.

RALZA B. FREEMAN.
